UNITED STATES PATENT OFFICE.

LEWIS MARION PRATT, OF ELDORADO, KANSAS, ASSIGNOR OF ONE-HALF TO ROY AUSTIN MEDLIN, OF ELDORADO, KANSAS.

CATCH FOR SCREEN-DOORS AND THE LIKE.

1,379,040.

Specification of Letters Patent.

Patented May 24, 1921

Application filed May 1, 1920. Serial No. 378,265.

To all whom it may concern:

Be it known that I, LEWIS M. PRATT, a citizen of the United States, residing at Eldorado, in the county of Butler and State 5 of Kansas, have invented a new and useful Catch for Screen-Doors and the like, of which the following is a specification.

This invention relates to a catch especially designed for use in connection with screen 10 doors and the like, one of the objects of the invention being to provide a simple, durable and efficient device which can be applied readily to a screen door or similar structure and which will hold the door in 15 shut position and also allow it to be opened readily by the application of sufficient pressure thereto.

A further object is to provide a structure 20 of this character which is cheap to manufacture and will not readily get out of order.

With the foregoing and other objects in view, which will appear as the description proceeds, the invention resides in the combination and arrangement of parts and in 25 the details of construction hereinafter described and claimed, it being understood that, within the scope of what is claimed, changes in the precise embodiment of the 30 invention shown can be made without departing from the spirit of the invention.

In the accompanying drawings the preferred form of the invention has been shown.

In said drawings—

35 Figure 1 is an elevation of one edge of a door and showing the catch connected thereto.

Fig. 2 is a section on line 2—2, Fig. 1, and showing the keeper engaged by the catch.

40 Fig. 3 is a section on line 3—3, Fig. 2.

Referring to the figures by characters of reference A designates a portion of a door structure having a recess *a* formed in one edge thereof and B designates a portion of 45 a door casing having a recess *b* formed therein. A strike plate 1 is secured to the door frame B and has a longitudinal slot 2 therein. Secured to the door A is a face plate 3 having a circular opening 4 therein and secured to the back face of this plate 3 so as to be supported freely within the open-

ing *a* is a spring strip 5 having a circular opening 6. A ball 7 projects into the opening 6 and also into the opening 4, the diameters of both these openings being less than 55 the greatest diameter of the ball so that said ball will be pressed normally against the wall of the opening 4 by the spring strip 5. When the ball 7 is thus located it projects beyond the face plate 3 and into the path of 60 the strike plate 1. Thus it will be seen that when the door A is swung to closed position, the ball 7 will come against the strike plate 1 and be pushed backwardly into the recess 65 *a* in the door and against the action of the spring strip 5. The ball will not, however, leave the opening 4. As soon as the ball 7 arrives opposite the opening 2 in the strike plate 1, the spring 5 will press the ball into 70 said opening so that the door will be held in 75 closed position. When it is desired to open the door it is merely necessary to pull or push upon it with sufficient force to cause the ball 7 to be deflected out of the opening 2 and back against the spring strip 5 a sufficient distance to allow the door to shift out of closed position.

It will be seen that the device is very simple, compact and durable, is cheap to manufacture, and can be attached readily to a 80 door.

What is claimed is:

The combination with a strike plate having an elongated opening therein, there being a recess back of the strike plate, of a 85 door having a recess extending longitudinally within one edge thereof, a face plate extending across the recess and having a circular opening therein, said opening, when the door is closed, being in register with a 90 portion of the elongated opening in the strike plate, an elongated spring strip within the recess and secured at one end to the face plate, said spring having a circular opening in the free end portion thereof, and 95 a ball of a diameter greater than the diameters of the openings in the face plate and in the spring, said ball being normally clamped between the face plate and the spring and with a portion thereof projected through the 100 opening in the face plate for engagement in the opening in the strike plate, said ball

having a rolling contact with the strike plate during the movement of the door to open or closed position, the spring being extended longitudinally along lines extending across the plane of rotation of the door during such rolling contact.

In testimony that I claim the foregoing

as my own, I have hereto affixed my signature in the presence of two witnesses.

LEWIS MARION PRATT.
